UNITED STATES PATENT OFFICE.

EDMUND B. POWERS, OF NEW YORK, N. Y., ASSIGNOR TO EMPIRE RAILWAY APPLIANCE CORPORATION, OF NEW YORK, N. Y., A CORPORATION OF NEW YORK.

ANTICREEPING DEVICE FOR RAILWAY-RAILS.

1,168,671.

Specification of Letters Patent.

Patented Jan. 18, 1916.

Application filed December 24, 1914. Serial No. 878,966.

To all whom it may concern:

Be it known that I, EDMUND B. POWERS, a citizen of the United States, residing in the city of New York, borough of Brooklyn, in the county of Kings and State of New York, have invented a certain new and useful Improvement in Anticreeping Devices for Railway-Rails, of which the following is a specification.

10 The invention relates to that class of anticreeping devices in which the rail is held to a tie-plate by the engagement of a roller in an angular space provided between the base-flange of the rail and an adjacent angular face on a lug formed on the tie-plate, and the object of the invention is to provide reliable and economical means for holding the roller against vertical movement and consequent escape from such angular space.

20 The invention consists in certain novel features of construction and arrangement by which the above objects are attained, to be hereinafter described.

The accompanying drawings form a part 25 of this specification and show an approved form of the invention.

Figure 1 is a plan view showing a portion of a rail supported upon and in engagement with a tie-plate constructed in accordance 30 with the invention. Fig. 2 is a section taken transversely of the rail, on the line 2—2 in Fig. 1. Fig. 3 is a top view of the roller on a larger scale, and Fig. 4 is a corresponding side elevation.

35 Similar letters of reference indicate the same parts in all the figures.

A is the head of the rail and A¹ A² the base-flanges supported on a tie-plate B secured to the tie, not shown, by spikes D or other suitable fastening means. On the plane upper face of the tie-plate at one end is an abutment B¹ against which lies the outer flange A¹ of the rail and on the opposite end is a lug B² having its face next adjacent to the flange A² vertical and inclined angularly to the edge of the flange, and preferably inclined in opposite directions from the center of the lug to form an obtuse angle as indicated in dotted lines at b² b² in Fig. 1. In 40 the angular space thus provided is received a rotatable member or vertically arranged roller E, preferably cylindrical, and toothed or corrugated peripherally in the axial direction as at E¹, the better to engage the edge of

the flange A² and adjacent angular face b² 55 and adapted to be forced by the endwise movement or creep of the rail into the gradually narrowing portion of the angular space until it reaches a position at which further movement in that direction is impossible and 60 thus holds the rail against further creep relatively to the tie-plate. The double angularity of the face of the lug prevents release by a retrograde movement of the rail and insures permanent engagement. 65

To prevent vertical movement of the roller E a flange or lip B³ is provided on the lug B² overhanging the angular space and overlapping upon the upper face of the roller. The depth of the rabbet thus provided or the vertical distance between the upper face of the tie-plate and under face of the lip B³ is 70 enough greater than the height of the roller to permit the latter to move freely therein, and the lip overhangs sufficiently to hold the 75 roller against vertical displacement.

In applying the roller the edge of the outer flange A¹ of the rail is engaged against the abutment B¹ with the base of the rail in an inclined position, the roller E is then inserted 80 beneath the lip B³ and at or near the center of the obtuse angle formed by the faces b² b² of the lug B², the rail is then turned down into full contact with the tie-plate, with the edge of the inner flange A² against the exposed periphery of the roller, and the spikes D driven. The roller is preferably of such diameter as to require considerable force to be exerted in thus placing the rail, so that the corrugations E¹ on the roller will slightly indent or bite into both the edge of the base-flange A² and face b², thus insuring the engagement of the roller with those surfaces and compelling the roller to move with the rail. 95

Modifications may be made in the forms and proportions of the parts. The lip B³ may overlap the roller to a greater or less degree than shown, it being only necessary that the lip shall extend far enough to engage the 100 roller reliably.

I claim:

1. In a device of the character set forth, a tie-plate adapted to support a rail, a lug on said plate having an angular face adjacent to such rail, a cylindrical flangeless roller in the angular space between said angular face and rail and engaging the base-flange of the rail, 105

and a lip on said lug constructed to overhang said angular space and roller and prevent vertical movement of the latter.

2. In a device of the character set forth, a tie-plate adapted to support a rail, a lug on said plate having two angular faces adjacent to such rail and forming an obtuse angle one with the other, a cylindrical flangeless roller in the angular space between said angular faces and rail and engaging the base-flange

of the rail, and a lip on said lug constructed to overhang said angular space and roller and prevent vertical movement of the latter.

In testimony that I claim the invention above set forth I affix my signature, in presence of two witnesses.

EDMUND B. POWERS.
